(57) **CLAIM**

The ornamental design for a lid for beverage container, as shown and described.

DESCRIPTION

FIG. 1 is a front perspective view of a lid for beverage container, showing our new design;

FIG. 2 is a front view of the lid for beverage container illustrated in FIG. 1;

FIG. 3 is a rear view of the lid for beverage container illustrated in FIG. 1;

FIG. 4 is a left-hand side of the lid for beverage container illustrated in FIG. 1;

FIG. 5 is right-hand side of the lid for beverage container illustrated in FIG. 1;

FIG. 6 is a top view of the lid for beverage container illustrated in FIG. 1; and,

FIG. 7 is a bottom view of the lid for beverage container illustrated in FIG. 1.

The broken line showing of the beverage container illustrates environment and forms no part of the claimed design. All other broken lines illustrate portions of the lid for beverage container that form no part of the claimed design.

1 Claim, 6 Drawing Sheets
